UNITED STATES PATENT OFFICE

ANTONE J. AMBROSE, OF WESTVILLE, ILLINOIS

DESIGN FOR A BEDSTEAD OR SIMILAR ARTICLE

Application filed June 18, 1931. Serial No. 40,262. Term of patent 3½ years.

To all whom it may concern:

Be it known that I, ANTONE J. AMBROSE, a citizen of the United States, residing at Westville, in the county of Vermilion and State of Illinois, have invented a new, original, and ornamental Design for a Bedstead or Similar Article, of which the following is a specification, reference being had to the accompanying drawing, forming part thereof.

The figure is a view in perspective showing my new design for a bedstead or similar article.

I claim:

The ornamental design for a bedstead or similar article as shown.

MR. ANTONE J. AMBROSE.
